waltung und Verwertung von gewerblichen
Schutzrechten mit beschränkter Haftung, Ber-
lin, Germany, a corporation of Germany

Application October 22, 1938, Serial No. 236,433
In Germany January 22, 1938

3 Claims. (Cl. 250—27.5)

The invention relates to discharge devices and especially to the type of discharge device having multiple electrodes such as the screen grid tubes, pentodes and so forth.

An object of the invention is to provide a substantially linear characteristic between the anode current and the grid potential in the above mentioned tubes, and especially such tubes used as amplifier tubes.

Other objects and advantages of the invention will be apparent from the following description and drawing in which:

Fig. 1 is a graph illustrating the characteristic between the anode current and the grid potential in tubes of the prior art.

Fig. 2 is a cross sectional view of a discharge device disclosing a preferred embodiment of the invention.

Fig. 3 is a graph disclosing the linear characteristic between the anode current and grid potential of the device in Fig. 2.

Fig. 4 is a cross sectional view through a duplex set of electrodes embodying the invention.

Fig. 5 is a cross sectional view through a tube embodying the invention and having a multiple set of electrodes.

It is highly desirable to have a linear characteristic between the anode current and the grid potential throughout the range of current values for the tube. Unfortunately, however, as established by Langmuir, the current in the anode circuit is proportional to the root of the third power of the control grid potential. Where additional grids or auxiliary electrodes are utilized in addition to the control electrode, the linearity of the tube characteristic is further disturbed by the presence of these additional grids. The distribution of the cathode current between the screen grid and anode does not take place in the same ratio for operating conditions, but is dependent upon the magnitude of the screen grid potential and the anode potential or the effective potential in the space between the two. By proper selection of the external resistance, the upper portion of the tube characteristic, in regard to anode current and grid potential, can be made satisfactorily linear.

In Fig. 1 the anode current is plotted as ordinate and the grid potential is plotted as abscissa. The curve 1 illustrates the characteristic of anode current to grid potential for triodes and screen grid tubes without external resistance, as established by the Langmuir Discharge Law. By the use of external resistance, the upper portion

of the curve can be made substantially linear as illustrated in the heavy black line extending above the operating point 2. The portion of the curve line below the operating point 2 has, however, a relatively large curvature 3 and it is one of the objects of the present invention to change this relatively large curvature into a substantially linear relationship so that the line will be substantially linear throughout the various anode current values of the tube.

In Fig. 2 is illustrated a preferred embodiment of the invention for obtaining a substantially linear characteristic of the tube. In the drawing, the numeral 4 is the cathode which, as illustrated, is formed as substantially an arc segment having a concave electron emitting surface. The control grid 5 and the screen grid 6, if used, are also preferably curved segments concentric with the concave surface of the cathode 4. At substantially the normal focal point of the concave cathode 4 and its associated control and screen grids, 5 and 6, is located an auxiliary electrode 7. This auxiliary electrode 7 is preferably in the form of a perforated plate, or mesh, lying symmetrically with respect to the curved cathode and the control and screen grids. The plane of the auxiliary electrode 7 is within the plane bisecting the curved segment 4 of the cathode. The anode 9 is also preferably in the form of a plate lying within the same plane as that of the auxiliary electrode 7, which plane, as previously mentioned, bisects the curved segment of the cathode. This position of the anode 9 makes a lower capacity between the anode and the other elements. Intermediate the auxiliary electrode 7 and the anode 9 may be located a second screen grid 8. If desired, the grid 8 may be utilized as a braking or suppressor grid. The auxiliary electrode 7 has preferably a fixed positive potential.

The device of Fig. 2 operates in the following manner: The curvature of the concentric electrodes is selected that for smaller currents, the intersection point of the electron streams falls on the auxiliary electrode 7. The auxiliary electrode 7 accordingly has a comparatively large current because it is impinged upon by many electrons that are absorbed thereby, instead of being passed on to the anode. If the tube current is made larger, then the electron stream is broadened out and the concentration point is displaced towards the anode. The current which the auxiliary electrode absorbs becomes continually smaller with increasing tube current. Finally, for large currents, a substantially smaller

portion of the current is taken up by the auxiliary electrode. It is possible by the selection of the position of the auxiliary electrode, its size and its construction, to influence the relationships in such manner that the current drawn through the auxiliary electrode is in the desired ratio to the tube current. Therefore, the lower portion of the characteristic of the tube between anode current and grid potential may be made substantially rectilinear. The radial position of the plane anode in respect to the cylindrical segment of the cathode 4 provides a broad region for the focusing and attracting of electrons thereto. Heat of the anode is also more effectively radiated.

These relationships are illustrated in Fig. 3. Instead of the curved portion 10, the tube, constructed according to the invention disclosed in Fig. 2, will have a straight line characteristic 11 in its lower portion. This straight line characteristic is provided by the auxiliary electrode taking a current which is the magnitude of the difference of the current values of the characteristics between the curved line 10 and the straight line 11 illustrated by the fine black lines extending between the two curves for various values of grid potential.

The use of the second screen grid 8 between the anode 9 and the auxiliary electrode 7 is of advantage, because it shuts out the influence of the anode potential and makes the position of the intersecting point on the characteristic curve independent of the magnitude of the instantaneous anode potential. Because of this fact, the invention, from a practical standpoint, is especially adapted for screen grid tubes. It will be noted, also, that the desired rectilinearity of the characteristic may be obtained without any decrease in the steepness of the curve.

Either a directly heated or an indirectly heated cathode may be used. However, it is preferred to use an indirectly heated cathode since the desired concave curvature can be easily formed and then coated with the usual electron emitting coating.

Fig. 4 discloses a further modification of the invention, utilizing a duplex set of electrodes. In this disclosure, the second screen grid also serves as a diaphragm for the purpose of better focusing the electron rays. No lost currents are absorbed by this second screen grid. In this figure, the cathode 12 is illustrated as having two concave electron emitting surfaces, emitting in opposite directions. Adjacent to each of these surfaces is the concentrical curved control grid 13 and the normal screen grid 14. The auxiliary electrode 15 has its position similar to that illustrated in

Fig. 2. The second screen grid 16, however, is constructed as a diaphragm for concentrating the electron stream to impinge upon the anode 18. The braking or suppressor grid 17 may be used if desired. The dotted lines in Fig. 4 illustrate diagrammatically the more crowded electron paths coming from certain cathode areas with increased current over that in Fig. 2, and the more distant focus of these electron paths beyond the auxiliary electrode.

Fig. 5 has a schematic showing of a plurality of electron systems joined together in a suitable manner to form a unitary system for high powered tubes. The cathode is formed of four curved surfaces, 19, 20, 21, and 22, which are joined together as illustrated with electron emitting paths concentrated in four different directions. The corresponding control grids, as well as auxiliary electrode and anodes, are illustrated corresponding to those of Fig. 2. The cathode may, of course, be either directly or indirectly heated. The invention illustrated in Fig. 5 has the advantage, however, that a centrally arranged heating body may be used for all four of the electron emitting surfaces, if an indirectly heated cathode is utilized. The corresponding electrodes in the systems in Fig. 4 and 5 may be connected together within the tube if desired.

It is apparent that many modifications may be made in the form, number, and arrangement of the elements disclosed without departing from the spirit of the invention.

I claim:

1. A discharge device comprising an envelope containing an anode, and cathode, said cathode having a concave electron emitting surface, and an auxiliary electrode having a surface for the impingement of electrons thereon substantially at the focal point of said concave surface, and a screen grid intermediate said auxiliary electrode and said anode, said screen grid having an opening therethrough for directing electrons to said anode.

2. A discharge device comprising a concave cathode, a concave control electrode and a plane anode, and an auxiliary electrode intermediate said anode and the group of said concave cathode and control electrode, said auxiliary electrode being in a plane aligned with said plane anode.

3. A discharge device comprising an envelope containing a cathode having a surface whose section is an arc, a plane anode and a plane auxiliary electrode, said anode and auxiliary electrode being in a plane substantially bisecting said arc and also being spaced from each other in said plane.

MARTIN HARNISCH.
